STOKER

Erle S. Ormsby, St. Louis, Mo.

Application August 2, 1940, Serial No. 350,020

3 Claims. (Cl. 110—38)

This invention relates to stokers; and has special reference to stokers having movable grates and a ram for delivering measured quantities of coal onto the movable grates.

Objects of the invention are to provide an improved stoker comprising a ram for delivering measured quantities of fuel onto a series of inclined grates controlled and operated by the ram, in a manner to cause a part of the fresh fuel to pass under the body of ignited and burning fuel adjacent to the ram; to provide a cooperation of the ram and the grates that will greatly increase the capacity of the stoker to burn fuel rapidly over the entire grate area; to provide a relative arrangement of the grates and the ram whereby at least a part of each fresh charge of fuel into the furnace is forced under the burning bed of fuel within the furnace; to provide means for operating the inclined grates in a manner to break up or stir and reshape the burning fuel within the furnace; to provide a novel form of combustion arch for causing the lean or thin gases from the ash-pit area to mix with the high volatile gases given off from the incoming fresh fuel which is in the process of ignition, and to increase the furnace temperature in the smoke-consuming area at the front of the combustion arch; to provide cooperating elements associated with the grates for increasing the capacity or ability to burn high volatile or smoke producing fuels almost completely and without giving off visible smoke in objectionable quantities; to provide a bank of grates supported between the ram and the movable grates for supporting the fuel to provide combined underfeed and overfeed ignition of the coal delivered into the furnace by the ram; and to provide an adjustable device for controlling and regulating the amount of coal delivered into the furnace at each operation of the ram.

Other objects will appear from the following description, reference being made to the annexed drawings, in which—

Fig. 1 is a vertical longitudinal sectional view of my improved stoker and grate mechanism showing the ram in retracted position.

Fig. 2 is an enlarged sectional view showing the connections for reciprocating the ram and controlling extent of movement of the grates.

Fig. 3 is a vertical sectional view showing the ram in an intermediate position.

Fig. 4 is a similar sectional view showing the ram in its forward position to close the opening into the furnace.

The coal hopper 1 is located at the front of the

furnace and is provided with an inclined chute 2 leading to the gate arch 3. The bottom of the hopper 1 and of the chute 2 comprises an inclined wall 4 for supporting the fuel within said hopper and chute, and a ram 5 for forcing the fuel from the hopper through the space 6 below the gate arch 3. The combined bottom wall and ram is mounted for reciprocating movements on rollers 7 and along the upper end of the steep stationary grate 8. The space 6 is between the gate arch 3 and the upper end of the grate 8. The grate 8 is rigidly supported by bars 9.

A link 10 pivotally connects the movable combined bottom wall and ram with a crank device 11 mounted on a support 12 and rotated by driving connections 13 from a motor 14. It is apparent that, when the crank 11 is rotated, the combined bottom wall and ram will be moved from retracted position shown in Fig. 1 to the position shown in Fig. 4, in which the ram 5 is within the space 6 and has forced fresh fuel downwardly along the grate 8 under the previously ignited fuel, and has also forced a part of the fresh fuel over and onto the previously ignited fuel. This obtains combined underfeed and overfeed ignition of the fuel as it is forced into the furnace by the ram. When the ram is in the advanced position shown in Fig. 4, the space 6 is substantially closed thereby.

The moving grate comprises a series of bars 15 having their lower ends supported upon tubular rollers 16 mounted on a support 17 and their upper ends supported by a bar 18 attached to the lower ends of a number of operating links 19. The lower ends of the operating links 19 are operatively supported by rollers 20 mounted on a stationary support 21. The links 19 extend upwardly and forwardly and are provided with slotted pivot connections 22 with the movable bottom and ram device. The slotted connections 22 may be varied and interchanged as desired to regulate the extent of movement of the movable grate bars 15 with respect to the combined ram and movable bottom of the coal hopper. Ordinarily it is not desirable to move the grate bars 15 as far as the ram and bottom is moved. The fact that the grate bars 15 are to be oscillated by operation of the ram 4 implies that there is sufficient looseness between the parts 4, 19 and 15 to permit the grate bars 15 to be operated as described. This is familiar mechanical practice.

The movable grate bars 15 are arranged to receive the burning fuel from the stationary grates 8. Movement of said grates 15 breaks up or stirs and reshapes the burning fuel thereon somewhat

as would be effected by use of a poker or slice-bar, or the like. The lower ends of the grates 15 are engaged by a tie-rod 23 which prevents relative vertical displacement thereof.

The lower ends of the movable grates 15 operate over and along the upper ends of angular stationary grates 24 having their upper ends mounted on a single bar 25 and their lower ends engaging a retaining bar 26. Longitudinal movement of the grates 15 discharges the ashes and other solid remnants onto the stationary grates 24 and thence into the ash-pit 27 beyond the grates 24 and adjacent to the bridge wall 28.

The combustion arch 29 of refractory material extends forwardly from the bridge wall 28 and is formed with a downwardly extended or drop arch 30 across its forward end. The drop arch 30 is separated from the gate arch 3 by a space 31. This arrangement causes the lean gases from the ash-pit area and from the rear of the burning fuel bed to move forwardly toward the space 31 and into the smoke consuming area, where they become mixed with the high volatile gases rising from the incoming fresh fuel during the process of ignition. When the lean and high volatile gases are mixed in this manner, complete combustion results so that there is substantially no visible smoke passing from the furnace.

A shaft 32 extends across the inlet end of the chute 2 and supports a wall or plate 33 that may be moved to different adjusted positions within and across the chute to vary the area of the inlet end thereof and thus regulate the amount of fuel passing into the chute. A removable lid or door 34 may be mounted in an opening in the upper wall of the chute 2 to afford means for inspection of the inside of the chute.

It should now be apparent that this invention attains all of its intended objects and purposes efficiently and satisfactorily. The device may be manufactured and installed at comparatively low cost and will continue to function for an indefinite period of time as a highly efficient combustion device. The construction and arrangement of the parts may be varied within the scope of equivalent limits without departure from the nature and principle of the invention.

I claim:

1. In a furnace, an arch member, a stationary inclined grate rigidly supported below and cooperating with said arch member to form a fuel inlet, a ram inclining downwardly and inwardly for movement into said inlet to deliver fuel through said inlet onto said grate, mechanism for

operating said ram to deliver fuel through said inlet and onto said grate inwardly beyond said inlet, links pivotally attached at their outer ends to said ram outwardly beyond said grate for inward and outward movement by said ram, means for supporting the inner ends of said links, a transverse bar attached to said links below said grate, an inclined grate below and inwardly beyond said stationary grate arranged to receive fuel from said stationary grate and having its outer end supported by said bar for operation thereby during operation of said ram, and means for supporting the inner end of said last named grate.

2. In a furnace, an arch member, a stationary inclined grate rigidly supported below and cooperating with said arch member to form a fuel inlet, a ram inclining downwardly and inwardly for movement into said inlet to deliver fuel through said inlet onto said grate, mechanism for operating said ram to deliver fuel through said inlet and onto said grate inwardly beyond said inlet, a number of links, means pivotally connecting the outer ends of said links with said ram for operation thereby, an anti-friction device supporting the inner ends of said links, a transverse bar attached to said links below said grate, an inclined grate below and inwardly beyond said stationary grate arranged to receive fuel from said stationary grate and having its outer end supported by said bar for operation thereby during operation of said ram, and means for supporting the inner end of said last named grate.

3. In a furnace, an arch member, a stationary inclined grate rigidly supported below and cooperating with said arch member to form a fuel inlet, means cooperating with said arch member to form an outlet for the products of combustion, a ram inclining downwardly and inwardly for movement into said inlet to deliver fuel through said inlet onto said grate substantially below said outlet, mechanism for operating said ram to deliver fuel through said inlet and onto said grate inwardly beyond said inlet, an inclined grate below and inwardly beyond said stationary grate and immediately below said outlet arranged to receive fuel from said stationary grate, and links having their outer ends pivoted to said ram for movement thereby and having their inner ends connected to the outer end of said last named grate for moving said last named grate during operation of said ram.

ERLE S. ORMSBY.
